UNITED STATES PATENT OFFICE.

JOHN H. FORNEY, OF BURLINGTON, IOWA.

MAIL-BOX.

SPECIFICATION forming part of Letters Patent No. 724,092, dated March 31, 1903.

Application filed May 7, 1902. Serial No. 106,248. (No model.)

To all whom it may concern:

Be it known that I, JOHN H. FORNEY, a citizen of the United States, and a resident of Burlington, in the county of Des Moines and State of Iowa, have made a certain new and useful Invention in Mail-Boxes; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a perspective view of my mail-box. Fig. 2 is a vertical transverse section of the same.

This invention has relation to mail-boxes, and has for its object the provision of a box of this character especially adapted to the needs of persons residing in the country or farmers for the reception of mail-matter deposited therein for collection by the carrier or by the persons to whom it is addressed.

With this object in view the invention consists in the novel construction and combination of parts, all as hereinafter described, and pointed out in the appended claims.

Referring to the accompanying drawings, the letter A designates a metal box about six inches in width, eight inches high, and eighteen inches long. The box is provided with a rounded or concave false bottom B, doing away with corners and causing mail-matter, stamps, coins, and other articles deposited to drop to the center of the box, where they can be readily removed. This false bottom has an oblique extension to the upper edge of the front of the box, thus facilitating the removal of mail-matter from the box. The lid or cover C of the box is of plane character and is sloping or oblique and is so constructed as to prevent entrance of snow or rain, having lateral and rear flanges c for this purpose and being provided forwardly with a depending bead or bend c', inclosing a rod-weight at r and designed to serve as convenient means for raising the cover with a gloved hand, at the same time keeping the cover securely closed at all times.

At the rear of the box and in the center thereof is secured a spring-stop D, against which the cover B abuts at the limit of its

upward movement, preventing jar and wear and facilitating the self-closing of the box.

E is a signal device to indicate that mail-matter has been deposited and aiding the carrier in his work. This device consists in the present case of a metal plate painted some color which will attract attention, preferably red, and connected to the box by a chain in such manner that it may be hidden within the box or may hang without and in front of the same.

The hinges of the box-cover are arranged forwardly of the rear edge of the box, and the rear water-excluding flange of the cover operates in conjunction with or fits over a plane forwardly and upwardly extending oblique portion C' at the rear of the box, such oblique portion C' having a substantially right-angular relation to the cover C when closed. The box is thus to some extent cut away at the rear, which will provide for the action of the spring-stop D and the raising of the cover without undue interference with an attachment-post or the like.

The casing or outer box A is preferably of rectangular form, and the false bottom is held away therefrom by its fastenings at the edges, so that it is protected from becoming deformed or otherwise injured from accident or rough usage. The front or lip portion of the concave bottom is made convex, as at v, in order to guard the contents of the box when being removed, preventing the letters from catching or harshly engaging the beaded margin z of the opening of the box. At this point z the oblique extension to the upper edge of the box-front fits under a rearward bend of said edge.

Having thus described my invention, what I claim as new, and desire to secure by Letters Patent, is—

1. A mail-box, having a plane forwardly and upwardly directed extension at the rear, the oblique or sloping plane hinged cover having a substantially right-angular relation to said extension, when closed and having a rear water-excluding flange adapted to fit over said extension, and having lateral water-excluding flanges, substantially as specified.

2. A mail-box, having the bottom of general rectangular form, and having the rearward bend at the upper edge of the front thereof,

the concave false bottom of said box fitting under said bend at the top, and having a convexity adjacent thereto, substantially as specified.

- 5 3. A mail-box, having the bottom of general rectangular form, and the concave false bottom fitting therein, and having an oblique extension to the upper edge of the front of the box, substantially as specified.
- 10 4. A mail-box, having a forwardly and upwardly directed extension at the rear, the oblique or sloping hinged cover having a rear water-excluding flange adapted to fit oversaid

extension, and having lateral water-excluding flanges, and a forward depending bend 15 or bead inclosing a rod-weight, and a spring device for limiting upward movement of the cover, and lying within the space left by said extension, substantially as specified.

In testimony whereof I affix my signature 20 in presence of two witnesses.

JNO. H. FORNEY.
